DESIGN FOR A GLOVE

Alice Frances Bates, New York, N. Y.

Application January 21, 1939, Serial No. 82,506

Term of patent 3½ years

To all whom it may concern:

Be it known that I, Alice Frances Bates, a citizen of the United States of America, residing in the city of New York, county of New York, and State of New York, have invented a new, original, and ornamental Design for a Glove, of which the following is a specification, reference being had to the accompanying drawing, forming part thereof,

Fig. 1 is a side perspective view of a glove embodying my design and showing the little finger and palm portion thereof.

Fig. 2 is a side perspective view of the same showing the palm portion and index finger thereof.

The back of the glove is conventional.

I claim:

The ornamental design for a glove, substantially as shown and described.

ALICE FRANCES BATES.
